Primary Examiner—Kay H. Chin

(21) Appl. No.: **29/169,691**
(22) Filed: **Oct. 23, 2002**

(57) **CLAIM**

The ornamental design for computer mouse with baseball
bat shape, as shown.

DESCRIPTION

(51) LOC (7) Cl. **14-02**
(52) U.S. Cl. **D14/403**
(58) Field of Search D14/402-410,
D14/417, 432; 200/5 R, 5 A, 6 R, 6 A,
302.1, 512-517; 273/148 B; 345/156-167;
74/471 XY; 463/36, 37, 38

(56) **References Cited**

FIG. 1 is a perspective view of a computer mouse showing
our new design;

FIG. 2 is a side elevational view thereof;

FIG. 3 is a bottom perspective view thereof; and,

FIG. 4 is a top plan view thereof.
